UNITED STATES PATENT OFFICE.

TIMOTHY B. POWERS, OF BROOKLYN, NEW YORK, ASSIGNOR TO JACOB B. BANDER, OF NEW YORK, N. Y.

BRACKET FOR SIGNAL-CASINGS.

1,334,048.

Specification of Letters Patent. Patented Mar. 16, 1920.

Application filed October 22, 1919. Serial No. 332,500.

To all whom it may concern:

Be it known that I, TIMOTHY B. POWERS, a citizen of the United States, residing at Brooklyn, in the county of Kings and State 5 of New York, have invented certain new and useful Improvements in Brackets for Signal-Casings, of which the following is a specification.

This invention relates to supporting 10 means in the nature of a bracket, whereby articles of various kinds can be supported from a side wall thereof, to be attached to or carried by a suitable member, and which is adjustable for attachment to a face or wall 15 of the member at different angles between the horizontal and vertical.

One of the objects of the invention is to provide an adjustable bracket of this nature that can be very economically formed out of 20 several pieces of sheet metal, simply cut out and bent up, without the employment of machine tools, except for several perforations; and which device will be of very small weight in comparison with the strength and 25 rigidity thereof.

A further object of the invention is to provide such a construction that is of a special advantage to support casings containing electrical devices, such as lamps and 30 number plates or electro-magnetic operating members; whereby the conducting wires can be passed through the several members of the bracket, from the place of securement into the attachment side of the casing, and 35 be thereby practically concealed and protected against injurious action, as well as being not visible.

In the accompanying drawing showing one embodiment of my invention, Figure 1 40 shows the device as supporting a signal casing on the rear mud-guard of an automobile.

Fig. 2 is a vertical section through the device, and a portion of the casing to which it is attached.

Fig. 3 is a cross section on the line 3—3 of Fig. 2.

Fig. 4 shows in front and side elevations, the loop member.

Fig. 5 is a side elevation of the supporting member.

Fig. 6 is a front elevation of the latter.

Fig. 7 is a plan of the same member.

Figs. 8 and 9 show the two washers used in the loop.

55 The device comprises essentially three

members, the supporting member shown in Figs. 5—7, the loop member shown in Fig. 4, and a bolt by which these two members are secured together in adjusted positions.

The supporting member as shown is 60 formed of a single piece of sheet metal, and comprises a body portion of substantially channel form having opposite parallel side walls 2 and 3 connected by an end wall 4, see Fig. 7. At the upper end the side walls 65 have perforations 5 and 6 that register, to receive a clamping bolt 7 having a nut 8 thereon.

This end of the supporting member is preferably enlarged to form substantially 70 circular ears 9 and 10, that contain the said perforations 5 and 6. At its other end this body of channel form has three laterally projecting arms 11, 12 and 13, that are integral extensions of the said three walls 2, 3 75 and 4, of the body. These form a base for securement of the support at the place of attachment.

The other principal member of the bracket comprises a loop 14, of suitable 80 sheet metal bent to form about two-thirds of a circle, see Fig. 4, with the end portions of the loop extended for securement to an upright wall of the article. As shown, the loop 14 has transverse extensions 15 and 16 85 at the end portions, that project in opposite directions in substantially the same plane, but which may be slightly curved if the purpose is for attachment to an article having a cylindrical wall, such as a signal casing 90 17, shown in Fig. 1. This loop member will have the extensions suitably apertured to be riveted or otherwise secured to the casing 17, as shown in Fig. 2, whereby the loop extends vertically with its axis horizontal.

The width of the loop member is substantially the same as the distance apart of the ears 9 and 10 of the support, whereby the loop can be inserted between these ears. 100 Also the diameter of the loop is slightly less than the diameter of these ears, whereby the opposite edges of the loop can engage the inner walls of the ears, and the bolt 7 thereupon passes through the apertures of the 105 ears, and the nut applied, to draw the ears together and clamp them against the side edges of the loop. If desired, one or more apertured disks, such as 18 and 19, are inserted in the loop 14, and fit on the bolt, 110

whereby to position or center the loop in the ears, to be substantially concentric therewith. But it is to be understood that these disks are only needed for assembling these parts, and the drawing together of the side wall of the support against the edges of the loop will serve to retain the loop member rigidly secured to the support.

It will be understood from Figs. 1 and 2 that on loosening the bolt or nut, the loop member can be swung on a horizontal axis on the support, which will serve to bring the support to extend at various angles to the upright wall of the casing 17. This is of a special advantage where it is desired to support the casing 17 on a curved mud-guard 20 of an automobile, so that the casing can be supported in various positions, and the place of securing of the support can vary its angle in a wide range between the horizontal position and an upright position.

Where this form of bracket is employed with a casing or article that is to be supplied with electric current, the loop 14 is provided with an opening 21, and the wires 22 can pass through an opening in the mud-guard and pass through the channel form body of the support, then through the opening 21 in the loop, then out of the loop between its extensions, and through an opening in the wall 23 of the casing 17, as shown in Fig. 2. It will be seen that these wires are thereby concealed and protected from injury, as well as being invisible.

It is to be understood that a bracket of this sort can be used to support a large variety of articles. It is formed substantially of two pieces of sheet metal bent to proper shape by simple dies, and the device is assembled by merely a simple clamping bolt. This bracket is also of especial advantage in supporting the rear number plate of an automobile, or the combined number plate and rear lamp that serves to illuminate the number plate as well as show the usual rear signal in red.

What I claim is:—

1. A bracket composed of a support and a holder adjustably secured to the support, the holder comprising a strip bent to form a loop with the end portions extended for securing to the article; a support comprising a body of open channel form with the opposite parallel sides at the top apertured to have the opposite edges of the holder loop engage the inner opposed faces; and a bolt passing through the apertured sides and the loop to draw the sides inwardly against the loop edges and clamp the holder to the support in adjusted positions.

2. A bracket composed of a support and a holder adjustably secured to the support, the holder comprising a strip bent to form

a loop with the end portions extended for securing to the article; a support comprising a body of open channel form with the opposite parallel sides at the top apertured to have the opposite edges of the holder loop engage the inner opposed faces; a bolt passing through the apertured sides and the loop to draw the sides inwardly against the loop edges and clamp the holder to the support in adjusted positions, the channel body of the support having three outwardly extending divergent arms one projecting from each of the three walls of the channel portion to form a base for securing of the support to the place of attachment.

3. A bracket composed of a support and a holder adjustably secured to the support, the holder comprising a strip bent to form a loop with the end portions extended for securing to the article, and a support comprising a body of open channel form with the opposite parallel sides at the top apertured to have the opposite edges of the holder loop engage the inner opposed faces; a bolt passing through the apertured sides and the loop to draw the sides inwardly against the loop edges and clamp the holder to the support in adjusted positions, the channel body of the support having three outwardly extending divergent arms one projecting from each of the three walls of the channel portions to form a base for securing of the support to the place of attachment, and a washer located inside of the loop engaging the bolt and the inner wall of the loop to position the loop in the support, the loop having an opening to the channel opposite the base, and also having the end portions separated for the concealed passage of conducting wires from the article through the bracket to the base support.

4. A bracket composed of a support and a holder adjustably secured to the support, the holder comprising a strip bent to form a loop with the end portions laterally extended and projecting in opposite directions for securing to the article; a support comprising a body of open channel form with the opposite parallel sides at the top extended to form apertured ears arranged to have the opposite edges of the holder loop engage the inner opposed faces of the ears near their margins; and a bolt passing through the apertured ears and the loop to draw the ears inwardly against the loop edges and clamp the holder to the support in adjusted positions.

5. A bracket composed of a support and a holder adjustably secured to the support, the holder comprising a strip bent to form a loop with the end portions laterally extended and projecting in opposite directions for securing to the article; a support comprising a body of open channel form

- with the opposite parallel sides at the top extended to form apertured ears arranged to have the opposite edges of the holder loop engage the inner opposed faces of the ears near their margins; a bolt passing through the apertured ears and the loop to draw the ears inwardly against the loop edges and clamp the holder to the support in adjusted positions, the channel body of the support having three outwardly extending divergent arms one projecting from each of the three walls of the channel portion to form a base for securement of the support to the place of attachment.
6. A bracket composed of a support and a holder adjustably secured to the support, the holder comprising a strip bent to form a loop with the end portions extended for securement to the article; a support comprising a body of open channel form with the opposite parallel sides at the top extended to form apertured ears arranged to have the opposite edges of the holder loop engage the inner opposed faces of the ears near their margins; a bolt passing through the apertured sides and the loop to draw the sides inwardly against the loop edges and clamp the holder to the support in adjusted positions, and an apertured disk inside of the loop freely slideable on the bolt and engaging the inner wall of the loop to position the loop in the ears.
7. A bracket composed of a support and a holder adjustably secured to the support, the holder comprising a strip bent to form a loop with the end portions extended for securement to the article, and a support comprising a body of open channel form with the opposite parallel sides at the top apertured to have the opposite edges of the holder loop engage the inner opposed faces; a bolt passing through the apertured sides and the loop to draw the sides inwardly against the loop edges and clamp the holder to the support in adjusted posi-
- tions, the channel body of the support having three outwardly extending divergent arms one projecting from each of the three walls of the channel portions to form a base for securement of the support to the place of attachment, the loop having an opening to the channel opposite the base, and also having the end portions separated for the concealed passage of conducting wires from the article through the bracket to the base support.
8. A bracket composed of a support and a holder adjustably secured to the support, the holder comprising a strip bent to form a loop with the end portions laterally extended and projecting in opposite directions for securement to the article; a support comprising a body of open channel form with the opposite parallel sides at the top extended to form apertured ears arranged to have the opposite edges of the holder loop engage the inner opposed faces of the ears near their margins; a bolt passing through the apertured ears and the loop to draw the ears inwardly against the loop edges and clamp the holder to the support in adjusted positions; the channel body of the support having three outwardly extending divergent arms one projecting from each of the three walls of the channel portions to form a base for securement of the support to the place of attachment, and a washer located inside of the loop engaging the bolt and the inner wall of the loop to position the loop in the ears; the loop having an opening to the channel opposite the base, and also having the end portions separated, for the concealed passage of conducting wires from the article through the bracket to the base support.

Signed at New York city, N. Y., on October 21st, 1919.

TIMOTHY B. POWERS.
